CIRCUIT BREAKER

Leon R. Ludwig, Buffalo, N. Y., and William H. Stuellein, East McKeesport, and Gayne D. Gamel, Verona, Pa., assignors to Westinghouse Electric Corporation, East Pittsburgh, Pa., a corporation of Pennsylvania

Original application June 9, 1944, Serial No. 539,450. Divided and this application August 3, 1948, Serial No. 42,314

11 Claims. (Cl. 200—97)

1

This invention relates to circuit breakers and, more particularly to circuit breakers embodying electromagnetic tripping means for instantaneously tripping the breaker in response to over-load currents above a predetermined value and after a time delay in response to overloads of lesser value.

This application is a division of copending application Serial No. 539,450, filed June 9, 1944, by Leon R. Ludwig, William H. Stuellein, and Gayne D. Gamel, now Patent No. 2,504,855, issued April 18, 1950, and assigned to the assignee of the present application.

An object of the invention is to provide a circuit breaker having an electromagnetic trip device embodying an improved, adjustable time-delay device.

Another object of the invention is to provide a circuit breaker having an electromagnetic trip device with a mechanical time-delay device embodying a simple adjusting means for selectively adjusting the amount of time delay provided by the time-delay device.

Another object of the invention is to provide a circuit breaker having an electromagnetic trip device embodying a time-delay device comprising an adjustable mechanical escapement mechanism.

Another object of the invention is to provide an electromagnetic trip circuit breaker embodying an improved time-delay device that is of simple and rugged construction, accurate and reliable in operation, and inexpensive to manufacture.

The novel features that are considered characteristic of the invention are set forth in particular in the appended claims. The invention itself, however, both as to structure and operation, together with additional objects and advantages thereof, will be best understood from the following detailed description of one embodiment thereof when read in conjunction with the accompanying drawings, in which:

Figure 1 is a vertical sectional view through the center pole of a three-pole circuit breaker embodying the principles of the invention;

Fig. 2 is an enlarged vertical sectional view of the trip mechanism;

Fig. 3 is a horizontal sectional view of the trip mechanism taken on line III—III of Fig. 2, showing the time-delay device;

Fig. 4 is a sectional view taken on line IV—IV of Fig. 2;

Fig. 5 is a fragmentary view partly in section on line V—V of Fig. 2 showing the latch mechanism;

2

Fig. 6 is a sectional view taken on line VI—VI of Fig. 2 showing the cooperation of the latch member with the tripping toggle; and

Fig. 7 is a sectional view taken on line VII—VII of Fig. 2.

Referring to Figure 1 of the drawings, the circuit breaker is provided with an operating mechanism common to all of the poles of the breaker. The operating mechanism is mounted 10 in a U-shaped frame 17 having sides which are rigidly connected by a cross member 19. The frame 17 is mounted on the central portion of a base 11 of insulating material and is secured thereto by means of bolts 21 and 23. The outer 15 ends of the frame are rigidly connected by a cross member 25.

A shaft 29 extending through openings in the sides of the frame 17 pivotally supports a pair of contact-arms 31 having their free ends integral with a contact-arm 30 for the center pole. The contact-arms (not shown) for the outer poles of the breaker are identical with the contact-arm 30 for the center pole, but are not provided with arms 31. The contact-arms for the 25 outer poles are rigidly secured to a tie-bar 67 which extends across all of the poles and which is securely clamped to the center-pole contact-arm 30 by means of split clamp 70 and a screw 11. The three contact-arms are thus mechanically connected for movement together. Rectangular tubes 69 of insulating material between the tie-bar 67 and the contact-arms 30 for the several poles serve to insulate the three movable contact-arms and their associated contacts from 35 the tie-bar 67.

The movable contact structures and the stationary structures for the several poles are alike; hence only the contacts for the center pole are illustrated. The contact-arm 30 pivotally carries 40 a main movable contact-member 47 and a movable arcing contact-member 55 which cooperate respectively with a main stationary contact 39 and a stationary arcing contact 37. The stationary contacts 39 and 37 are secured to a conductor 41 which extends through an opening in the base 11 and forms a terminal-connector 45. Contact pressure for the main contacts is provided 45 by a spring 53 disposed between the contact-arm 30 and the main movable contact-member 47. Similarly, a spring 63 provides contact pressure 50 for the arcing contacts.

When the contact-arm 30 is moved to open the contacts, the arc drawn across the arcing contacts 55—37 by rupture of the current is drawn into an arc-extinguisher indicated generally at 76 where it is cooled and extinguished. Any

suitable arc-extinguisher may be employed, the one shown comprising, generally, a stack of slotted plates (not shown) of magnetic material disposed adjacent the path of travel of the arcing contact-member 55.

The movable arcing contact-member 55 is connected by a flexible shunt conductor 77 to the main movable contact-member 47, and another flexible shunt conductor 79 connects the contact-member 47 to a conductor 81. The conductor 81 extends downwardly forming the energizing means for a tripping electromagnet (to be later described) and is secured at its lower end by means of a bolt 82 to the inner end of a terminal-connector 83 which, together with the terminal-connection 45, serves to connect the breaker in an electrical circuit.

The electrical circuits for the several poles of the breaker are essentially the same. The circuit for the center pole extends from the terminal 45 through the conductor 41, the main contact-members 39-47, the flexible shunt conductor 79, the conductor 81 to the terminal 83. The circuit for the arcing contacts 37-55 extends from the terminal 45, through the conductor 41, the arcing contact-members 37-55, the flexible shunt conductor 77, the main contact-member 47, and through the previously described circuit to the terminal 83.

The contact-arms 30 are biased in a clockwise or opening direction by means of a pair of springs 85 (only one being shown). These springs are tensioned between the center-pole contact-arm 30 and a fixed pivot 87 supported in the main frame 17. In the closed position of the breaker, the center-pole contact-arm and consequently all of the contact-arms are releasably restrained in the closed contact position by means of a toggle and linkage mechanism which is collapsible to cause opening of the contacts. The toggle and linkage form a part of the common operating mechanism.

This collapsible linkage includes a yoke-shaped lever 89 pivotally mounted on a fixed pivot 91 supported on the main frame 17. The lever 89 is operatively connected to the support arms 31 of the center-pole contact-arm 30 by a main operating toggle comprising toggle-links 93 and 95. The toggle-link 93 has one end pivoted on a pin 101 supported on the lever 89, and the link 95 is pivoted on a pivot pin 99 in the arms 31. The links 93 and 95 are pivotally connected by a knee-pivot pin 97. The toggle-link 95 comprises a pair of links rigidly connected by means of an integral cross-bar 115.

The free end of the lever 89 is pivotally connected by means of a link 103 to one arm of a lever 105 pivoted on the fixed pivot 87. The other end of the lever 105 is pivotally connected to a toggle-link 107 of a tripping toggle comprising the link 107 and a toggle-link 109. The link 109 is pivoted on a fixed pivot 113 supported on the frame 17. The toggle-links 107 and 109 are pivotally connected by a knee-pivot pin 111. The lever 105 and the link 103 each comprises a pair of members rigidly connected by yokes substantially as illustrated.

The above-described linkage serves to releasably hold the contact structure including the movable contacts for all of the poles of the breaker in closed contact position. In the closed position, the main operating toggle 93-95 is over center above a line through the centers of the pins 99 and 101, and a second toggle, one link of which comprises the overcenter links 93-95 and

the other link of which comprises the lever 89, is overcenter above a line through the centers of the pins 99 and 91. The overcenter movement of the main operating toggle 93-95 is limited by the projecting end of the link 93 engaging the cross-bar 115 of the link 95.

With the main operating toggle 93-95 and the toggle comprising the links 93-95 and the lever 89 in the overcenter position, the springs 85 bias the lever 89 in a clockwise direction. Clockwise movement of the lever 89, however, is normally prevented by the tripping toggle 107-109 which is restrained in a slightly underset position by a latch member 117 (Figs. 1, 2 and 5) cooperating with an extension 119 of the toggle-link 107. As will be described hereinafter, the latch-member 117 may be operated to release the extension 119 and permit collapse of the toggle 107-109 and opening of the contacts. In its restrained position, the tripping toggle 107-109, acting through the lever 105 and the link 103, prevents clockwise movement of the lever 89, and consequently holds the movable contacts in closed position against the biasing influence of the springs 85.

The latch-member 117 is adapted to be actuated to cause collapse at the tripping toggle to effect opening of the contacts by means of an overload-trip device indicated generally at 133, or by a shunt-trip device indicated generally at 138. The overload-trip device 133 is operable in response to overload currents in the circuit of the breaker to rotate the latch 117 and cause collapse of the tripping toggle 107-109. The shunt-trip device is adapted to be energized from any suitable source separate from the circuit of the breaker to move the latch 117 axially and cause the collapse of the tripping toggle 107-109 independently of the overload-trip device 133.

When rotated by the trip device 133, or moved axially upwardly by the trip device 138, the latch-member 117 releases the extension 119 of the toggle-link 107 and permits collapse of the tripping toggle 107-109 which permits clockwise rotation of the lever 89 thus permitting the springs 85 to actuate the movable contact structure clockwise (Fig. 1) to open the contacts.

The main operating toggle 93-95 does not immediately collapse, but the force of the springs 85 applied through the contact-arms 30-31 and the main operating toggle causes collapse of the toggle comprising the links 93-95 and the lever 89 which results in a clockwise movement of the lever 89. This movement is transmitted through the link 103 and the lever 105 to complete the collapse of the tripping toggle 107-109.

The clockwise or opening movement of the contact-arms 30-31 is arrested by projections (not shown) thereon striking the frame 17. At this time, the rebound of the inertia of the main-operating toggle 93-95 and the parts of the linkage 89, 103 and 105 starts the main-operating toggle 93-95 over center in a direction to cause its collapse. By the time the knee pin 97 of the toggle has passed over center below the line 99-101, the weight of the parts acts to complete the collapse of the toggle 93-95 and causes the linkage 89, 103, 105 and the tripping toggle 107-109 to be automatically reset to their normal holding positions and relatched. The main toggle 93-95 remains in collapsed condition until the contacts are closed.

The contacts are closed manually by clockwise rotation of the handle 141. This movement of the handle, through connections not shown, thrusts a link 151 downwardly, and, due to the engagement of the link with a projection 153 on

a yoke-shaped closing lever 145, rotates the closing lever in a clockwise direction. The closing lever 145 comprises a pair of spaced levers disposed on the outside of the frame 17 and are pivotally supported on the fixed pivot 91. Clockwise movement of the closing lever 145 engages a roller 155 pivotally carried on the inner end of the lever with the toggle link 93, now in its collapsed position, and moves the toggle 93-95 to its overcenter position. Since at this time the tripping toggle 107-109 has been restored to its holding position and relatched, rotation of the lever 89 is prevented, and consequently the force applied by the roller 155 to straighten the operating toggle 93-95 rotates the contact-arms 30 counterclockwise to close the contacts and tension the springs 85.

The handle 141 is restored to its normal position by means of a spring 159 tensioned between the closing lever 145 and the frame 17. Upon release of the handle following a closing operation, the spring 159 moves the closing lever 145 counterclockwise and, through the projection 153 and link 151, restores the handle 141 to its normal position.

The closing lever 145 may also be operated to automatically close the contacts through the agency of a motor 139 mounted on a plate (not shown), but which is attached to the side of the frame 17. The motor 139 may be energized from any suitable source, and when energized is adapted, through a suitable driving connection, to rotate a crank disc 130. The disc 130 carries an anti-friction roller 131 which, upon rotation of the disc, engages a cam face 132 on an arm 134, secured to the closing lever 145, and rotates the arm and the closing lever clockwise to effect closing of the contacts. As soon as the roller 131 passes out of engagement with the arm 134, the spring 159 acts to restore the lever 145 to its normal position. The motor 139 is deenergized by a suitable limit switch (not shown).

The circuit breaker may be tripped manually by rotation of the handle 141 through a small angle in a counterclockwise direction from its neutral position. Rotation of the handle 141 in tripping direction engages a projection 157 on the link 151 with an ear 161 formed on a plate 163 (Fig. 2) secured to a slide 165 disposed in an opening in the cross-member 25 of the frame 17 and slidable vertically on a pair of rods 167 mounted in the cross-member 25 of the frame. The lower portion of the slide 165 is formed over to provide a laterally extending part 169 which is adapted to engage a head 171 on the end of a projection 173 integral with or otherwise suitably attached to the latch member 117. Upon rotation of the handle 141 (Fig. 1) in tripping direction, the link 151 is moved upwardly. During this movement, the projection 157 (Fig. 2) engages the ear 161 and raises the slide 165. This movement engages the extension 169 with the head 171 and raises the latch member 117 to effect release of the tripping toggle 107-109 and opening of the contacts.

As previously set forth, the latch member 117 is rotated to release the underset tripping toggle 107-109 by means of the current-responsive trip-device 133. There is a trip-device 133 provided for each pole of the breaker, but since the trip-devices for the several poles are alike only the one for the center pole shown in Figs. 2 and 3 will be described.

The trip-device 133 (Figs. 2 and 3) includes a fixed magnetic core-member 175 provided with

pole-pieces 177 secured thereto by means of bolts 179 which also serve to clamp the parts to an insulating frame 181. The core-member 175 is surrounded by an insulating tube 183 to insulate it from the energizing conductor 81 which is looped around the core-member between the pole-pieces 177. The frame 181 is provided with a cross-member 185 integral therewith which is secured to the base 11 of the breaker by means of the bolt 82 by which the conductor 81 and the flexible conductor 79 are secured together and to the base 11. Mounted for rotation in the frame 181 is a shaft 187 having the legs 189 of a yoke or trip-bar 191 mounted thereon for movement relative thereto, the trip-bar 191 being operable by the trip-devices for all the poles. A headed and shouldered stud 193, secured to the yoke 191 by a nut 195, projects through an opening in a link 197 which connects the trip device to a time-delay device indicated generally at 213. The inner end of the link 197 is formed over at right angles as at 199 to cooperate with an armature 201 mounted on the shaft 187 for movement relatively thereto. The armature 201 is biased to unattracted position as shown in Fig. 2 by means of a spring 203 having one end attached to a spring-clip 205 secured to the free end of the armature and the other end attached to an adjustable member 207. The member 207 has a reduced portion disposed in a vertical slot 209 in the outer wall of the frame 181 and is provided with a thumb-screw 211 for clamping the member 207 in its adjusted position in the slot 209. By loosening the thumb-screw 211 and sliding the member 207 in the slot 209, the tension of the spring 203 may be varied thereby varying the minimum current value at which the trip-device will function to trip the breaker.

The trip-devices for the two outer poles of the breaker are the same as the trip-device for the center-pole with the exception that the yoke or trip-bar 191 is omitted and the armatures 201 for the outer poles are secured to the corresponding shafts 187 for movement therewith. On the end 40 of the shaft 187 adjacent the center-pole trip-device is secured a collar 215 (Fig. 3) having a projection 217 thereon which is adapted to engage a shoulder on a connector 219 of insulating material. The connector 219 is secured to a hub 50 221 which is rotatably mounted in a bearing in the side-wall of the frame 181 and is secured to the leg 189 of the yoke 191 for movement therewith. Two connections 219 are provided, one disposed on each end of the yoke 191 for operatively connecting the two outer pole-armatures 201 to the yoke so that any one of the armatures will operate the yoke, upon energization of its corresponding trip-magnet, without displacing the other armatures.

The link 197 (Fig. 2) comprises two members welded or otherwise suitably secured together at their left-hand ends and having their right-hand ends formed to straddle a ratchet-wheel 223 (Figs. 6 and 3). The ratchet-wheel 223 is rotatably supported in a housing comprising spaced-circular plates 225 and a cylindrical side-wall 227. The upper plate 225 is secured to the lower leg of a U-shaped bracket 229, which supports the shunt 70 trip-device 138, by means of a pair of bolts 231 and is spaced from the bracket by spacers 233 surrounding the bolts 231 (see also Fig. 4). The upper leg of the bracket 229 is secured to the spaced main frame-members of the circuit breaker by means of a pair of screws 235 (only

one being shown) and a pair of bolts 237 which extend through both plates 225, both legs of the U-shaped bracket 229 and threadedly engage the frame-members 17. Spacers 239 (Figs. 2 and 4) surrounding the bolts 237 serve to space the time-delay housing from the lower leg of the bracket 229 and spacers 241 (Figs. 2 and 3) also surrounding the bolts 237 space the upper and lower plates of the time-delay device-housing apart. The plates 225 are also rigidly joined by a headed screw 243 (Fig. 2) which passes through an opening in the lower plate and threadedly engages the upper plate 225. Surrounding the screw 243 is a sleeve 245 upon which is mounted a shouldered sleeve 247 supporting the ratchet-wheel 223.

As previously stated, the bifurcated end of the link 197 straddles the ratchet-wheel 223. The link 197 is connected to the ratchet-wheel by means of a pin and slot-connection comprising a pin 249 (Figs. 2, 3 and 4) which extends through both portions of the link 197, through an elongated slot 251 (Fig. 3) in the ratchet-wheel 223 and through a clearance-opening 253 (Fig. 4) in the upper plate 225 of the housing of the time-delay device. The lower end of the pin 249 is headed and a collar 255 threadedly engages the pin above the upper portion of the link 197 to retain the pin 249 in place in the assembly. The pin 249 projects through the clearance-opening 253 in the upper plate 225 for the purpose of rotatably actuating the trip-member 117 (Fig. 2) to trip the breaker in a manner more fully described hereinafter.

A spring 257 (Figs. 2 and 3) coiled about the sleeve 247 has one end hooked around the pin 249 and the other end hooked over the ratchet-wheel 223 in the manner shown in Fig. 3. Normally the spring 257 is not under tension, but when the link 197 is moved toward the left (Fig. 3) by the operation of the electromagnetic trip-device of any one of the poles of the breaker, the pin 249 places the spring under tension in a direction to cause counterclockwise rotation of the ratchet-wheel 223. The speed of rotation of the ratchet-wheel is governed by an oscillator 259, the two arms of which alternately engage the teeth of the ratchet in the usual manner.

The oscillator 259 is U-shaped and is mounted for oscillation on a pin 261 which is mounted in the legs of a U-shaped movable member 263 pivoted on the ends of the sleeve 245 surrounding the screw 243. The spaced ends of the upper leg of the oscillator 259 are formed downwardly as at 265 (Figs. 2 and 3) to engage the ratchet-wheel. The lower leg of the oscillator extends to the left to form a governing weight for the oscillator, a clearance opening being provided therein for clearing the sleeve 247.

The amount of time delay provided by the time-delay device is adjustably determined by adjusting the oscillator circumferentially relative to the ratchet-wheel. This adjustment is effected by rotating the member 263 in which the oscillator is mounted about its pivot on the sleeve 245. This adjustment is accomplished by means of a thumb-screw 267 having a threaded portion extending through an elongated annular slot in the sidewall 227 of the housing and threadedly engaging the yoke of the member 263. By loosening the thumb-screw 267 and rotating the U-shaped member 263 counterclockwise or clockwise, the oscillator is correspondingly moved in the same direction from the position in which it is shown in Fig. 3, respectively, lengthening or shortening the time delay.

As previously stated, the pin 249 projects through the clearance-opening 253 (Fig. 4) in the upper plate 225 of the time-delay device housing to operate the latch-member 117 and effect tripping of the breaker. The latch-member 117 is rigidly secured on the upper end of a trip rod 269 which extends vertically through the center of the shunt trip-device 138. A disc 271 secured on the lower end of the rod 269 is provided with two recesses 273 and 275 (Fig. 4). The pin 249 (Figs. 2, 3 and 4) extends upwardly through the recess 273 and a substantial distance above the disc 271. The side-walls of the recess 275 are adapted to engage a stop-stud 277 which projects upwardly from the upper plate 225 to limit the rotary movement of the disc and of the latch-member 117.

Referring particularly to Figs. 5, 6 and 7 of the drawings, the latch-member 117 is provided with a vertically disposed slot 279 into which the projection 119 of the tripping toggle-link 107 extends. The projection 119 has a latching shoulder 281 which normally rests against the periphery of the latch-member to restrain the tripping toggle in its slightly underset holding position. At the point of latching engagement of the shoulder 281 with the latch-member, the slot 279 has straight parallel sides and is disposed at a slight angle relative to the projection 119 as shown in Fig. 6. At the point where the projection 119 extends into the slot 279, the sides of the slot are flared as shown in Fig. 7 to permit unlatching rotation of the latch-member.

The operation of the trip-device and time-delay device is described as follows: Upon the occurrence of an overload-current in any pole of the breaker below a predetermined value, for instance, below 1000% of normal rated current, the armature 201 of the affected pole is attracted by the fixed magnetic core-member and pole-pieces. If the overload occurs in one of the outer poles of the breaker, the armature operates through the projection 217 (Fig. 3) to actuate the yoke or trip-bar 191 and move the link 197 toward the left. If the overload occurs in the center pole, the armature engages the formed over-end 199 of the link 197 to move the link toward the left. Leftward movement of the link 197 through the pin 249 and spring 257 rotates the ratchet-wheel 223 counterclockwise (Fig. 3) under the control of the oscillator 259 without substantially increasing the tension of the spring 257. After the mechanism has operated a predetermined distance, the pin 249 engages the wall of the recess 273 (Fig. 4) in the disc 271 and rotates the disc 271, the rod 269 and the latch 117 counterclockwise until arrested by the wall of the recess 275 striking the stop-stud 277. The movement of the disc 271 and the latch-member 117 after the engagement of the pin 249 with the disc is sufficient to align the straight portion of the slot 279 (Fig. 6) in the latch-member with the latching shoulder 281 on the projection 119 thereby permitting collapse of the tripping toggle 107-109 (Figs. 1 and 2) and opening of the contacts in the manner previously described.

The ratchet-wheel 223 is provided with a flat surface 283 the one end of which, during a tripping operation, passes the lower arm 265 (Fig. 3) of the oscillator, whereupon the pull of the magnet is unrestrained and instantaneously moves the pin 249 the remaining distance to trip the breaker. By moving the oscillator relative to the ratchet-wheel so that a greater or lesser number of teeth is required to pass the oscillator be-

fore the wheel escapes from the oscillator, a longer or shorter time delay may be effected.

As soon as the current is interrupted and the trip magnet is deenergized, the spring 203 acts to restore the armature 201 of the affected pole to its unattracted position. The yoke 191, link 197 and the time-delay device are restored to their unoperated positions by means of springs 282 (Figs. 2 and 3) having one end attached to the lower ends of the legs 189 of the yoke 191 and having their other ends attached to spring-studs 254 projecting from the sides of the housing 181.

Upon the occurrence of an overload current above 1000% of normal rated current or a short circuit, the armature 201 of the affected pole operates to instantaneously move the link 197 and pin 249 toward the left and rotate the latch 117 independently of the ratchet wheel 223 to instantaneously trip the breaker. In this case the force applied to the pin 249 by the armature is sufficient to flex the spring 257 without actuating the ratchet wheel 223, the pin 249 moving toward the left in the slot 251 in the ratchet wheel. As soon as the current is interrupted and the trip magnet is deenergized, the spring 203 restores the armature of the affected pole to its unattracted position and the springs 282 restore the yoke 191 and the link 197 to their normal positions.

The provision of the mechanical escapement time-delay device connected to the tripping yoke makes the trip-device shockproof since the yoke 191 (Fig. 2) is restrained against operation in response to shocks and jarring forces due to the inertia of the ratchet-wheel 223 and the oscillator 259. Undesirable tripping operation of the latch 117 in response to shocks transmitted to the trip-device in a horizontal direction through the supporting structure 11 and 181 and also through the supporting structure 17-229 to the time-delay device, is thereby prevented.

As was previously set forth, the latch-member 117 is moved axially upwardly by means of the shunt trip-device 138 to release the tripping toggle 107-109 to thereby cause collapse of the operating linkage and opening of the contacts. The shunt trip-device comprises a movable core-member 285 of magnetic material and an energizing winding 287. The movable core-member 285 is secured to a reduced portion of the rod 269 by means of a pin 286 and is adapted to lift the rod upon energization of the winding 287. The movable core-member is disposed for vertical movement in a tube 289 of non-magnetic material, the ends of which are seated in counterbores in the upper and lower legs of the U-shaped frame 229. The winding 287 is wound on a tube 291 of insulating material surrounding the tube 289 and is insulated from the legs of the bracket 229 by means of insulating plates 293. Disposed in the tube 289 above the movable core-member 285 is a secondary-movable core-member 295 also of magnetic material. The secondary core-member 295 is spaced apart from the movable core 285 by means of a spring 297 coiled about the rod 269, and is movable axially relative to the core-member 285 and the rod 269. The spring 297 is seated on top of the movable core 285 and in a counter-bore in the secondary core 295.

The winding 287 is energized from any suitable source (not shown) either automatically or by the closure of a manually operable switch (also not shown) in the energizing circuit. When the coil is energized, the movable core 285 is

attracted upwardly and thrusts the rod 269 and the latch-member 117 upwardly to free the tripping toggle 107-109 in the manner previously described in connection with the description of the manual tripping of the breaker. The upward movement of the rod 269 and latch 117 is limited by the disc 271 on the lower end of the rod striking a member 299 secured to the bottom leg of the bracket 229. Upon deenergization of the winding 287, the movable core 285, the secondary core 295, the trip-rod 269 and the latch 117 are all restored to their normal unattracted positions by the force of gravity.

The purpose of the separate secondary core-member 295 and the spring 297 is to absorb the kinetic energy of the movable core 285, the rod 269 and the latch 117 imparted thereto as a result of shocks or jarring forces, and thus prevent undesirable tripping of the breaker in response to shocks. The only force due to shock that would cause false tripping movement of the movable core 285 and the trip-rod 269 is in a vertical direction and comes from the supporting structure 11, 17 and 229. Any shock in a vertical direction imparted to the supporting structure will be transmitted to the movable core 285 which results in accelerating the movable core and the trip-rod 269 upwardly in tripping direction. The spring 297 is relatively weak and serves only to provide a desirable air-gap between the two core-members 285 and 295. When the movable core 285 and trip-rod 269 are moved upwardly in response to shock, the secondary core 295 will remain substantially stationary until the movable core strikes it. When this occurs, the secondary core 295 is accelerated upwardly, thereby absorbing substantially all of the kinetic energy of the movable core 285. At the same time, the spring 297 was compressed as the movable core 285 approached the secondary core 295, and the energy stored therein reacts to move the secondary core 295 upwardly. The result is that, after the collision of the core-members, the secondary core 295, having a higher rate of acceleration than the movable core 285, will rebound from the upper leg of the bracket 229 and strike the movable core 285, thus providing an additional retarding force which is effective to prevent upward movement of the latch 117 and tripping of the breaker in response to sudden shocks or jarring forces.

From the foregoing description it will be apparent that there is provided a circuit breaker having a main latch which is movable rotatably by any one of a plurality of overload trip-devices to trip the breaker and movable axially by a separate trip-device to trip the breaker. There is also provided a mechanical time-delay device for delaying tripping of the breaker by any one of the plurality of trip-devices, the time-delay device also serving to prevent rotary tripping operation of the latch in response to shocks. There is also provided means for preventing axial tripping movement of the latch in response to shocks. A further advantage of the invention lies in the adjustment of the oscillator of the time-delay device relative to the ratchet-wheel to vary the amount of time delay.

While the invention has been disclosed in accordance with the provisions of the patent statutes, it is to be understood that various changes in the structural details thereof may be made without departing from the spirit of the invention.

We claim as our invention:

1. In a circuit breaker, trip-means operable

in response to abnormal circuit conditions for effecting operation of said breaker, a time-delay device comprising a mechanical escapement mechanism operatively related to said trip-means for at times retarding operation of said trip-means, said time-delay device comprising a rotatable member, an oscillating member engaging said rotatable member for retarding the rotation of said member, a pivoted arm supporting said oscillating member for concentric movement about said rotatable member, and means for moving said arm to adjust said oscillating member about said rotatable member to vary the amount of time delay.

2. In a circuit breaker, a trip-member operable to cause circuit opening operation of said circuit breaker, electroresponsive means operable in response to predetermined abnormal circuit conditions to operate said trip member, a time-delay device for retarding tripping operation of said trip member in response to abnormal circuit conditions below said predetermined value, said time-delay device comprising a rotatable member and an oscillator cooperating therewith for retarding rotation of said rotatable member, pivot means for said rotatable member, and an arm mounted on said pivot means for adjusting said oscillator about the periphery of said rotatable member to vary the amount of time delay.

3. In a circuit breaker, a trip-member operable to cause circuit opening operation of said circuit breaker, electroresponsive means for operating said trip-member, a time-delay device for retarding operation of said trip-member in response to abnormal circuit conditions below a predetermined value, said time-delay device comprising a rotatable member having teeth about a portion of its periphery and an oscillator cooperating therewith to retard operation of said trip-member, said rotatable member after moving a predetermined distance being released from said oscillator to effect operation of said trip-member, spring means operatively relating said trip-member to said time-delay device to permit instantaneous operation of the trip-member in response to abnormal circuit conditions above said predetermined value, and a pivoted member supporting said oscillator for circumferential movement about the rotatable member to vary the number of oscillations required of said oscillator to effect tripping of the breaker.

4. In a multi-pole circuit breaker, a trip-member common to all of said poles and operable to cause automatic opening of said breaker, electroresponsive means for each pole operable upon the occurrence of abnormal circuit conditions in the related pole to operate said trip-member, a single time-delay device for retarding tripping operation of said trip-member in response to abnormal circuit conditions occurring in any pole of the breaker, said time-delay device comprising a rotatable member and an oscillator cooperating with said rotatable member to retard tripping operation of said trip-member, said rotatable member after a predetermined travel moving free of said oscillator to actuate said trip-member, and a member pivoted coaxially with said rotatable member and operable to adjust the oscillator about the periphery of said rotatable member to vary the amount of time delay.

5. In a multi-pole circuit breaker, a trip-member common to all of the poles and operable to cause automatic opening operation of said

breaker, electromagnetic means for each pole operable upon the occurrence of abnormal circuit conditions in the related pole to operate said trip-member, a single time-delay device for retarding tripping operation of said trip-member in response to abnormal circuit conditions below a predetermined value occurring in any pole of the breaker, said time-delay device comprising a rotatable member and an oscillator cooperating therewith to retard operation of the trip-member, said rotatable member after a predetermined movement being released from said oscillator to effect operation of said trip-member, a spring connecting the trip-member to said time-delay device to permit instantaneous operation of the trip-member in response to abnormal circuit conditions above said predetermined value occurring in any pole of the breaker, and a lever pivoted for concentric movement about said rotatable member for adjusting said oscillator about the periphery of said rotatable member to vary the amount of time delay.

6. In a circuit breaker, trip-means operable to cause circuit opening operation of said breaker, a time-delay device operatively related to said trip-means comprising a rotatable member and an oscillator engaging said rotatable member for retarding rotation of said rotatable member, said rotatable member after moving a predetermined distance being released from said oscillator to effect operation of said trip-means, and a pivoted lever for adjusting the oscillator about the periphery of said rotatable member to vary the distance said rotatable member is required to travel before it is released from said oscillator.

7. In a circuit breaker, trip-means operable to cause circuit opening operation of said operating mechanism, a time-delay device related to said trip-means to retard operation of said trip-means, said time-delay device comprising a rotatable member provided with teeth about a portion only of its periphery and an oscillator engaging said teeth to retard operation of said rotatable member, said rotatable member after moving a predetermined distance being released from said oscillator to effect operation of said trip-means, and a pivoted lever for adjusting said oscillator about the periphery of said rotatable member to vary the number of teeth required to pass said oscillator before said rotatable member is released.

8. In a circuit breaker, a trip-member operable to effect opening operation of said breaker, a time-delay device related to said trip-member for retarding operation of said trip-member, said time-delay device comprising a rotatable member having teeth formed about a portion of its periphery and an oscillator cooperating with said teeth and operable to retard rotation of said rotatable member, means operable in response to abnormal circuit conditions to rotate said rotatable member a distance sufficient to cause said member to escape said oscillator after a predetermined time delay to effect operation of said trip-member, a pivoted member supporting said oscillator for oscillatory movement, and manual means for moving said pivoted member to selectively position said oscillator about the periphery of said rotatable member to vary the amount of time delay.

9. In a circuit breaker, a trip-member operable to cause circuit opening operation of said breaker, a time-delay device related to said trip-member to retard operation of said trip-member, said time-delay device comprising a rotatable

member provided with teeth about a portion of its periphery and an oscillator engaging said teeth to retard operation of said rotatable member, said rotatable member after a predetermined travel being released from said oscillator to effect operation of said trip-member, a casing enclosing said time-delay device, a pivoted lever mounted in said casing for supporting said oscillator, common pivot means for said rotatable member and said lever, and manual means disposed outside of said casing and operable to move said lever to selectively position said oscillator about the periphery of said rotatable member to vary the amount of travel of said rotatable member before said rotatable member is released from said oscillator.

10. In a circuit breaker, trip-means operable to cause circuit opening operation of said breaker, a time-delay device operatively related to said trip-means comprising an oscillator and a rotatable member operatively engaging said oscillator for a portion only of its rotation to be retarded thereby and then rotating free of said oscillator to actuate said trip-means, electroresponsive means for actuating said rotatable member, and a pivoted lever supporting said oscillator and movable to position said oscillator about the periphery of said rotatable member to vary the amount of rotation of said rotatable member before it moves free of said oscillator.

11. In a circuit breaker, trip-means operable to cause circuit opening operation of said breaker, a time-delay device operatively related to said trip-means comprising an oscillator and a rotat-

able member operatively engaging said oscillator for a portion only of its rotation to be retarded thereby and then rotating free of said oscillator to actuate said trip-means, electroresponsive means for actuating said rotatable member, spring means between said electroresponsive means and said rotatable member to permit said electroresponsive means to instantaneously actuate said trip-means independently of said time-delay device, and a pivoted lever supporting said oscillator and movable to position said oscillator circumferentially about said rotatable member to vary the amount of rotation of said rotatable member before said rotatable member moves free of said oscillator.
